UNITED STATES PATENT OFFICE

ERNEST WANAMAKER, OF CHICAGO, ILLINOIS, ASSIGNOR TO KULP THEFTPROOF LAMP COMPANY, OF CHICAGO, ILLINOIS, A CORPORATION OF ILLINOIS

THEFTPROOF-LAMP CONSTRUCTION

Application filed March 26, 1928. Serial No. 264,750.

This invention relates to locking means or devices for locking electrical apparatus within supporting sockets and has particular reference to devices of this character for rendering electric lamp bulbs, plug fuses, and the like, theftproof.

The subject matter of this invention comprises a theftproof electric lamp so made that it may be inserted in a socket of the usual construction and yet which cannot be stolen or removed from the socket until after the lamp bulb or electrical apparatus has become broken and displaced.

The objects of this invention include the provision of a very simple, durable and inexpensive construction for the purposes desired, such construction embodying substantially the minimum number of parts and being dependable and certain in its operation.

In the accompanying drawings, which illustrate various embodiments of my invention, Fig. 1 is a sectional elevational view through the base portion of a lamp including the invention in one of its forms;

Figs. 2 and 3 are similar views illustrating other forms of the invention;

Fig. 4 is a sectional view of a part of the base portion of a lamp of the form shown in Fig. 3;

Fig. 5 is similar to Fig. 4 but illustrates still another embodiment of the invention, and Fig. 6 is a vertical sectional view of a part of the base portion of a lamp of the form shown in Fig. 2.

In general the invention as illustrated may comprise an electric lamp bulb 10, or other electrical device of conventional form, a base member 11 adapted to be securely cemented upon the stem or neck 12 of the lamp bulb or the like, and a threaded shell contact 13 embracing the base member 11 and designed to engage a conventional form of screw threaded electrical receptacle.

It will be understood that I do not desire to restrict the application of my invention to its use with lamp bulbs, since various other types of electrical apparatus, such as plug fuses, thermo-ionic valves, and the like, may be substituted for the lamp bulb 10, and ren-

dered theftproof in accordance with this invention.

The base member 11 may comprise a cylindrical shell contact 14 upon which the threaded shell contact 13 is loosely fitted. In the form shown in Fig. 1 the shell contact 13 may be secured against rotation in respect to the shell contact 14 by the use of an area or areas of frangible fibrous material as at 15, which may be secured both to the base 11 and the shell contact 13 by adhesive material or otherwise, according to methods hereinafter described. This securing means serves to initially fix the threaded shell contact 13 against rotation relative to the lamp base and lamp. Accordingly it will be observed that when the base member 11 is rotated, as by grasping the bulb 10 for inserting the lamp into a receptacle, the shell contact 13 will also be rotated because of the frangible fibrous connection 15. In this manner the threaded shell contact may be readily screwed into the receptacle. The lamp or other electrical apparatus may be thus inserted and removed from the receptacle as often as desired, as long as no abnormal rotational forces are exerted thereon. However, when it is desired to render the device theftproof, the threaded shell contact may be screwed home in a receptacle and then if an abnormal and additional force is exerted to screw the device further inwardly, the area or areas of fibrous material at 15 will be disrupted. Thereafter, the shell contact 13 will be free for rotational movement in respect to the base member 11 and, accordingly, when an attempt is made to remove the lamp from its receptacle by turning the bulb, the base member 11 will merely freely rotate within the threaded shell contact and without exerting rotational force upon such contact. Hence, the bulb or other apparatus, together with the base member 11 will be merely rotated and cannot be removed.

After the lamp or other electrical apparatus has become worn out so that it is desirable to remove the same, the operator may place a canvas or other bag over the glass portion of the lamp and thereupon break the lamp. The canvas bag will retain the parti-

cles of broken glass. Access may then be had to a flanged edge 16 on the threaded shell contact for removal thereof by the use of pliers or other suitable tools.

5 The threaded shell contact 13 may be permanently retained against longitudinal movement in respect to the lamp by means of the flange 16 at the lower edge of the contact and a flange 17 at the upper edge or end 10 thereof. The flange 16 is adapted to be spun over and to abut a beaded portion 18 formed upon the base member near its lower edge. The flange 17 is adapted to be spun over a flange portion 19 at the upper edge of the base 15 member 11.

The lower portions of the flange 16 may be preferably located well within the receptacle member in which the lamp is inserted. In this way the receptacle member serves to prevent 20 access to the threaded shell contact member and accordingly this member cannot be turned either inwardly or out of the receptacle by tampering while the lamp or other electrical apparatus is in operative condition.

25 As shown in Fig. 1, the interior of the base member 11 may be filled with a suitable cement to cement the base member to the neck of the bulb in the conventional manner. At the upper end of the base member 11 a center 30 contact 20 may be positioned and held in place by the use of an insulating end piece 21, which may be tightly fitted or molded into the upper end of the base member 11. Lead wires 22 and 23 from the lamp filament or 35 other electrical devices may be electrically connected to the contacts 13 and 20 respectively in any suitable and well known manner.

40 The area or areas of fibrous material 15 may comprise various kinds and grades of paper, cloth or other sheet insulating materials of suitable thickness and strength to insure the retaining of the parts together until the desired predetermined force is applied to disrupt this connecting means to 45 render the lamp theftproof. In order that the disruption may be made to take place along a predetermined line and to insure complete separation, the fibrous material may be 50 perforated or otherwise weakened a predetermined amount along the desired line of separation as at 24. (See Fig. 1 and also Fig. 2.) The inner peripheral edge of the area of sheet material 15 may, for example, 55 be glued or secured by a suitable adhesive to the insulation piece 21 and the outer peripheral edge of the same piece may be likewise secured as at 25 to the flange portion 17 of the threaded shell contact 13. If desired, 60 the inner peripheral edge may be clamped beneath the center contact 20, as at 26. In fact, suitable clamping or riveting means might be used at both the inner and outer edges of the fibrous piece 15. Where an 65 adhesive is used, I find it preferable to use

a non-granular adhesive such as an animal or vegetable glue of good quality or a sodium silicate cement or other cementitious and preferably non-granular cement, which may be applied and dried to form a highly tenacious film between the metallic surfaces and the fibrous material. The exact areas and thickness of the fibrous material will of course depend upon the strength of the material used, but a uniform quality of fibrous 75 material may be readily selected, so that with each lamp a certain uniform predetermined force only will be necessary for proper disruption of the initial securing means. Inasmuch as the fibrous material will be disrupted 80 along a predetermined line, which preferably may be made circular and concentric with the axis of the base, after disruption no further resistance will be offered to the free turning of the bulb parts in respect to the 85 threaded shell contact.

In Fig. 2 a similar form of lamp is illustrated in which the area of disruptible sheet material is indicated at 27 and may comprise an annular band of gummed cloth or gummed 90 linen paper or the like, as indicated, glued to the upper flange of the threaded shell 13 and to the insulation piece 21.

In the form of the invention illustrated in Fig. 3, a band of fibrous material as at 28 95 encircles the lower peripheral edge of the shell contact 14 and may be secured thereto at intervals by adhesive as indicated at 29. At alternate intervals this band of material may be secured as at 30 to the inside lower 100 peripheral edge 16 of the threaded shell contact 13. The band of fibrous material 28 may function in substantially the same manner as the fibrous disruptible means above described and it may be so made that when subjected 105 to a predetermined force, the connecting portions intermediate between the glued areas 29 and 30 will be disrupted or if desired, the fibrous material may be made of sufficient strength so that the disturbing force will 110 cause the glued areas to give way from the metallic flanges.

In the embodiment illustrated in Fig. 5, the lower peripheral flanges of the contact 14 and the threaded shell contact 13 are shown 115 initially fixed together by the use of disruptible areas as at 31, such areas comprising a composition mixture comprising, for example, one of the adhesives as above mentioned, mixed with an equal quantity of particles or 120 shreds of fibrous material. The number or dimensions of the areas 31 and the strength of material used may be so selected or chosen as to give an initial holding means of the desired strength, which upon the application 125 of a predetermined force would be disrupted to release the parts to render the lamp theft-proof.

With the embodiments shown in Figs. 1 and 2, the disruptible fibrous material may be 130

made, if desired, of a suitable color to harmonize with the natural color of the lamp base, or if preferred, some distinctive color may be utilized to readily indicate to the user that the lamp is of the theftproof form.

While I have described my improvements in detail and in connection with certain preferred forms thereof, I do not desire to be limited to such details or forms, since many changes and modifications may be made and the invention embodied in various different forms without departing from the spirit and scope of the invention in its broader aspects. Therefore, I desire to cover all modifications and forms coming within the language or scope of any one or more of the appended claims.

What I claim as new and desire to be secured by Letters Patent of the United States is:

1. An electric lamp comprising a bulb, and a shell contact and an insulated center contact therefor, means fixing the shell contact against longitudinal movement in respect to said bulb member, and an area of fibrous sheet material initially fixing said bulb against rotation in respect to said shell contact and purposely designed to be disrupted by the exertion of a predetermined force to effect such rotation.

2. An electric lamp, comprising a bulb member, a supporting base having a shell contact therefor, said shell contact and bulb being provided with means to prevent longitudinal separation but permitting relative rotation therebetween, a filament in said bulb, means for maintaining connection between said filament and said shell contact during relative rotation of said contact and the bulb, and a body of disruptible fibrous material affixed to and extending between said shell contact and said bulb member to normally prevent relative rotation therebetween.

3. In an electric lamp, a bulb, a supporting base having a shell contact therefor, fibrous insulating means for initially securing the bulb against rotation in respect to said shell contact, said means being purposely designed to be disrupted for permitting the bulb to be independently rotatable after the exertion of a predetermined force to effect independent rotation thereof, and means for maintaining electrical connection between the lamp filament and the shell contact regardless of the rotation of the bulb.

4. A theftproof base for electric lamps, comprising an inner shell, an outer screw threaded shell surrounding the inner shell, means to prevent relative longitudinal movement of the two shells, and a disruptible area of frangible sheet material securing the shells in respect to each other and serving to cause the conjoint movement of the two shells in the act of screwing the base into a usual lamp socket and being disruptible upon fur-

ther turning of the base in the same direction and thereby preventing the rotation of the screw threaded shell.

5. In combination, an enclosure for electrical apparatus, a cylindrical shell mounted on said enclosure, means for preventing unauthorized removal of the enclosure from the shell, said shell being provided with means for engaging a supporting receptacle by turning movement of said shell, and an area of fibrous insulating material initially fixing said enclosure against rotation in respect to said shell to normally permit insertion and removal of the shell in respect to a receptacle by turning said enclosure, said material being purposely designed to be disrupted by the exertion of a predetermined force to effect further inward turning of the enclosure in respect to the receptacle.

6. A theftproof base for electrical lamps, comprising an inner shell in which a lamp bulb is adapted to be fixed, an outer screw threaded shell surrounding the inner shell, means to prevent relative longitudinal movement of the two shells, and a sheet of disruptible insulating material for initially connecting the two shells adapting them to turn together to an extent sufficient to permit the seating of the lamp in the socket and thereafter upon further turning of the lamp in the same direction being disrupted, thereby preventing the rotation of the screw threaded shell and consequently preventing the removal of the lamp intact.

7. In a theftproof electric lamp, a bulb, a shell contact therefor, the shell contact being screw threaded for engagement with the conventional socket and also secured by a sheet of insulating material whereby the bulb is fixed against rotation in respect to said shell contact while the lamp is being inserted into a socket, said insulating material being purposely designed to be disrupted along a predetermined line for releasing the bulb for free rotation in respect to the shell contact after the exertion of abnormal force to effect independent rotation thereof.

8. A theftproof electric lamp comprising a bulb, a substantially cylindrical metallic shell permanently cemented to the stem thereof and electrically connected to one of the lamp filament terminals, a center contact connected to the other filament terminal, a threaded shell contact embracing said metallic shell, said threaded contact and said metallic shell being formed with portions to prevent relative longitudinal movement thereof, and an area of paper arranged to secure said shell in respect to said contact for preventing said threaded contact from turning in respect to the bulb while the lamp is being inserted in a receptacle by turning the bulb, said paper means being purposely designed to be disrupted by the exertion of a predetermined force to effect further inward

turning of the bulb in respect to the receptacle.

9. In combination an electric lamp bulb, a substantially cylindrical supporting and contact carrying member permanently cemented thereto, a threaded shell contact embracing said member, and a sheet of fibrous material for initially fixing said bulb against rotation in respect to said contact to normally permit insertion and removal of the threaded shell in respect to a receptacle by turning said bulb, but said fibrous material being purposely designed to be disrupted along a predetermined perforated or weakened line of separation by the exertion of an abnormal force to effect further inward turning of the shell in respect to a receptacle.

10. A theftproof base for electric lamps, comprising an inner shell, an outer screw threaded shell surrounding the inner shell, means to prevent relative longitudinal movement of the two shells, and a disruptible area of frangible sheet material securing the shells in respect to each other and serving to cause the conjoint movement of the two shells in the act of screwing the base into a usual lamp socket and being disruptible upon further turning of the base in the same direction and thereby preventing the rotation of the screw threaded shell, said sheet material being distinctively colored in order to clearly identify the base as being of the theftproof type.

11. In combination, an electrical device, means for supporting said device and for preventing its unauthorized removal, comprising a socket member for engaging a supporting receptacle upon applying to said member a predetermined movement, an element of disruptible fibrous material connecting said device and said socket member for normally preventing relative movement therebetween, but permitting such movement upon disruption of said element by the application of a predetermined force in the direction of said predetermined movement, whereby after the device has been mounted at a supporting receptacle, said element may be disrupted by the continued application of force, such disruption preventing the application of a reverse movement to said supporting means by movement of the device upon unauthorized attempts to remove the device, and means for preventing separation of said device from said supporting means.

12. In combination, an electrical device, a supporting member mounted on said device, said supporting member being provided with means for engaging a receptacle by applying a predetermined movement to said supporting member through movement of said device, said device being initially fixed against movement in respect to said supporting member by a disruptible area of frangible sheet material to normally permit insertion and removal of the supporting member in

respect to the receptacle, said frangible material being purposely designed to be disrupted by the exertion of a predetermined force to effect abnormal movement of the device in respect to the receptacle, whereby after such disruption the unauthorized removal of the supporting device from the receptacle by manipulation of the device is prevented, and means for preventing separation of the device from the supporting member notwithstanding disruption of said frangible material.

In testimony whereof I have signed my name to this specification.
